UNITED STATES PATENT OFFICE.

VANCE J. ANDERSON, OF BETHEL, OHIO.

DESIGN FOR A NECKTIE-HOLDER.

SPECIFICATION forming part of Design No. 31,774, dated October 31, 1899.

Application filed September 18, 1899. Serial No. 730,949. Term of patent 7 years.

To all whom it may concern:

Be it known that I, VANCE J. ANDERSON, a citizen of the United States, residing at Bethel, in the county of Clermont and State of Ohio, have invented and produced a new and useful Design for a Necktie-Holder, of which the following is a specification.

This invention is a new and useful design for a necktie-holder, the essential feature of the design residing in certain details herein-after fully described.

In the drawings forming a part of this specification, Figure 1 is a perspective view of my tie-holder, and Fig. 2 is a side elevation of the same.

Referring now to the drawings by reference-

numerals, 5 indicates a substantially rectangular plate having outwardly-turned prongs 6 at its respective corners. A reduced extension 7 projects from this plate, and at their junction is a shoulder 8. This extension is shaped to form a series of transverse ribs or corrugations 9 and terminating in a flat end 10.

Having thus fully described my invention, what I claim as new, and desire to secure by Letters Patent of the United States, is—

The design for a tie-holder, substantially as shown and described.

VANCE J. ANDERSON.
